Primary Examiner — Katherine A Holbrow*Assistant Examiner* — Riya Salil Kamat(74) Attorney, Agent, or Firm — Suiter Swantz IP(57) CLAIM

The ornamental design for an inflatable slide, as shown and described.

DESCRIPTION

FIG. 1 is a perspective view of an inflatable slide, showing my new design;

FIG. 2 is a top plan view thereof;

FIG. 3 is a bottom plan elevation view thereof;

FIG. 4 is a left side view thereof;

FIG. 5 is a right side view thereof;

FIG. 6 is a front elevation view thereof; and,

FIG. 7 is a rear elevation view thereof.

The broken lines illustrate portions of the inflatable slide that form no part of the claimed design.
